(57) **CLAIM**

The ornamental design for a slide and ladder assembly, as shown and described.

DESCRIPTION

FIG. 1 is a front perspective view of the slide and ladder assembly design.

FIG. 2 is a rear perspective view of the slide and ladder assembly design of FIG. 1.

FIG. 3 is a front view of the slide and ladder assembly design of FIG. 1.

FIG. 4 is a rear view of the slide and ladder assembly design of FIG. 1.

FIG. 5 is a right side view of the slide and ladder assembly design of FIG. 1.

FIG. 6 is a left side view of the slide and ladder assembly design of FIG. 1.

FIG. 7 is a top view of the slide and ladder assembly design of FIG. 1; and,

FIG. 8 is a bottom view of the slide and ladder assembly design of FIG. 1.

The broken line showing of texture on the ladder stair-step top surfaces in FIGS. 1, 2, 4, and 7, a broken line protrusion centrally located on the rear surface of the slide in FIGS. 2, 4-6, and 8, and a broken line protrusion on the forward edge of each of the ladder side-rails in FIGS. 3, 5, 6, and 8 is included for the purpose of illustrating and forms no part of the claimed design.

1 Claim, 8 Drawing Sheets
